(57) **CLAIM**

The ornamental design for a stirrer tool for espresso, as shown and described.

DESCRIPTION

FIG. 1 is a front, right, and top perspective view of a stirrer tool for espresso, showing my new design;

FIG. 2 is a rear, left, and bottom perspective view thereof;

FIG. 3 is a front view thereof;

FIG. 4 is a rear view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, left, and bottom perspective view of the stirrer tool for espresso shown in a partially retracted position;

FIG. 10 is a front, left, and bottom perspective view of the stirrer tool for espresso shown in a fully retracted position;

FIG. 11 is a front, left, and bottom perspective view of the stirrer tool for espresso shown in an alternate partially retracted position; and,

FIG. 12 is an enlarged view of an encircled area labeled "12" in FIG. 4.

The evenly dashed broken lines show portions of the stirrer tool for espresso that form no part of the claimed design. The dot-dash broken lines in FIGS. 4 and 12 illustrate the border of the enlarged detail views and form no part of the claimed design.

1 Claim, 12 Drawing Sheets
